UNITED STATES PATENT OFFICE.

HUGH C. BAKER, JR., OF NEW YORK, N. Y.

MANHOLE.

SPECIFICATION forming part of Letters Patent No. 761,750, dated June 7, 1904.

Application filed October 28, 1903. Serial No. 178,804. (No model.)

To all whom it may concern:

Be it known that I, HUGH C. BAKER, Jr., a subject of the King of Great Britain, residing at New York, in the county of New York and 5 State of New York, have invented certain new and useful Improvements in Manholes, of which the following is a specification, such as will enable those skilled in the art to which it appertains to make and use the same.

- 10 The object of this invention is to provide a manhole for electrical and other conduits of improved construction whereby the said construction is simplified and the cost thereof materially reduced, a further object being to 15 provide a manhole of the class specified with an improved cover; and with these and other objects in view the invention consists in a manhole constructed as hereinafter described and claimed.
- 20 The invention is fully disclosed in the following specification, of which the accompanying drawings form a part, in which the separate parts of my invention are designated by suitable reference characters in each of the 25 views, and in which—

Figure 1 is a central longitudinal section of a manhole made according to my invention; Fig. 2, a horizontal section thereof on the line 2 2 of Fig. 1; Fig. 3, a plan view with a part 30 of the cover removed; and Fig. 4, a view similar to Fig. 2, but showing a modification.

The manhole which forms the subject of this application is oblong in form in horizontal section and wider at one end than at the other, 35 the side walls thereof converging from the wider to the narrower end and being also slightly curved, while the end walls are also slightly curved and are substantially at right angles to the longitudinal diameter of the manhole. The said manhole comprises a bottom *a*, composed of concrete or other suitable material, a body portion *b*, and a cover *c*. The body portion *b* is composed of separate horizontal layers of bricks or blocks 40 composed of concrete material, and each of the layers of bricks or blocks is made up of four different styles or shapes of bricks or blocks, as shown in Fig. 2, the different styles or shapes of bricks or blocks being designated 45 by the reference characters *b*², *b*³, *b*⁴, and *b*⁵.

As shown in the drawings, it will be seen that two of the bricks or blocks *b*² are employed in each layer, and these bricks or blocks make up the smaller end of the said layer, while two of the bricks or blocks *b*³ are employed 55 and constitute the corners of the larger end of said layer, and two of the bricks or blocks *b*⁴ are employed one in each side of said layer, and three of the bricks or blocks *b*⁵, two of which are in the opposite sides of the layer 60 and one in the wider end thereof, and in practice the positions of the corner and end bricks or blocks are reversed in the separate layers in order to break joints.

In the form of construction shown in Fig. 65 2 the manhole is provided with conduits *d*, which pass thereto through the ends thereof, and with conduits *d*², which pass thereto at the opposite sides of the wider end thereof, and the conduits *d*² enter the manhole through 70 openings in the blocks *b*⁵, and one of the end conduits enters through the other block *b*⁵ in the wider end of the manhole, while the other enters through one of the blocks *b*² in the narrower end of the manhole. 75

It will be apparent that the size of the manhole in the longitudinal section and in transverse width may be regulated or may be made larger or smaller, as may be desired, by simply enlarging the bricks or blocks *b*² *b*³ *b*⁴ and 80 the brick or block *b*⁵ in the wider end of the separate layers which make up the body portion of the manhole.

The form of construction shown in Fig. 3 is exactly the same as that shown in Fig. 2 except that a different layer of the horizontal bricks or blocks that make up the body portion of the manhole is shown, and in this form of construction I have also shown a part of my improved manhole-cover, which comprises 90 a horizontal **T**-iron *e* and transverse **I**-beams *e*², three of which are employed, and said **T**-iron and **I**-beams form a frame which supports a cover composed of concrete bricks or blocks, four different styles or shapes of which 95 are employed and three of which are shown and designated by the reference characters *e*³, *e*⁴, and *e*⁵, and the concrete bricks or blocks which make up one side of the cover are exactly the same as those that make up the op- 100

posite side, the opposite side being formed by simply turning over or reversing the position of the bricks or blocks in the first-named side. The cover is also provided with a central opening e^6 , and for this purpose the T-beam e is composed of two parts, and around said opening is placed the usual collar e^7 , on which may be placed the usual removable cap, which is not shown.

- 10 In Fig. 4 I have shown a slight modification in which each of the horizontal layers which make up the body portion of the manhole is composed of four different styles of bricks or blocks the same as shown in Fig. 2; 15 but in this case the said bricks or blocks are slightly different in shape and dimensions, but the principle of construction is the same as in the said Fig. 4, and the different styles or shapes of bricks or blocks are designated by 20 the reference characters f , f^2 , f^3 , and f^4 , the bricks or blocks f forming the narrower end of the manhole, the bricks or blocks f^2 forming the corners of the wider end thereof, while the bricks or blocks f^3 form parts of the side 25 walls, the bricks or blocks f^4 being also used in the side walls and in the wider end of the manhole, and by varying the size of these bricks or blocks the manhole may be made of any desired dimensions in horizontal section without 30 changing the form thereof. The object in forming the manhole wider at one end than at the other is to facilitate the passage of the cables, which enter said manhole through the 35 conduit at the narrower end of the manhole, through the side conduits, and it will also be apparent that this form of construction also facilitates the passage of the cables straight through the manhole, or from end to end thereof, especially when a portion of the said cables 40 is to be passed through the side conduits.

Although I have described the bricks or blocks which make up the body portion and cover of the manhole as composed of concrete material, it will be apparent that the said bricks 45 or blocks may be composed of any material capable of being molded into the required form and possessing the necessary strength.

Having fully described my invention, what

I claim as new, and desire to secure by Letters Patent, is—

1. A manhole the body portion of which is composed of separate horizontal layers of bricks or blocks, said bricks or blocks being of four different styles or shapes and being adapted to be reversed in the separate layers so as to break the joints, substantially as shown and described. 50

2. A manhole, the body portion of which is composed of separate horizontal layers of bricks or blocks, said bricks or blocks being of four different styles or shapes and being adapted to be reversed in the alternate layers so as to break the joints, said manhole being also wider in horizontal section at one end than at the other, substantially as shown and described. 60 65

3. A manhole the body portion of which is composed of separate horizontal layers of bricks or blocks, said bricks or blocks being of four different styles or shapes, and said manhole being also provided with a cover composed of supporting beams or bars arranged at right angles to each other and bricks or blocks of four different styles or shapes, substantially as shown and described. 70 75

4. A cover for manholes composed of supporting beams or bars arranged at right angles to each other and bricks or blocks of four different styles or shapes, substantially as shown and described. 80

5. A manhole which is oblong in form and wider at one end than at the other, said manhole being provided with a cover of similar form and composed of beams or bars arranged at right angles to each other and bricks or blocks supported by said beams or bars, substantially as shown and described. 85

In testimony that I claim the foregoing as my invention I have signed my name, in presence of the subscribing witnesses, this 23d day of October, 1903. 90

HUGH C. BAKER, JR.
